UNITED STATES PATENT OFFICE.

EBENEZER STEVENS, OF LONDON, ENGLAND.

IMPROVED MACHINE FOR MAKING DOUGH, PASTE, &c.

Specification forming part of Letters Patent No. 40,370, dated October 20, 1863.

To all whom it may concern:

Be it known that I, EBENEZER STEVENS, of No. 139 Cheapside, in the city of London, a subject of the Queen of Great Britain, have invented or discovered new and useful improvements in machinery for preparing dough and paste suitable for making bread, biscuits, pastry, cakes, and similar articles; and I, the said EBENEZER STEVENS, do hereby declare the nature of the said invention and in what manner the same is to be performed to be particularly described and ascertained in and by the following statement thereof—that is to say:

This invention has for its object improvements in machinery for preparing dough and paste suitable for making bread, biscuits, pastry, and cakes. By means of this machinery dough and paste may be prepared without the materials being handled or touched by the operator. The process is thus rendered perfectly cleanly, whereas the hand process, as ordinarily practiced, is the reverse of this. The use of the machinery described also results in promoting the health of the employed, in a great saving of labor, and in a great increase in the yield of bread, which also is of a better quality. For this purpose machinery is constructed in the several manners shown in the annexed drawings, which I will now proceed to describe.

The drawings A show a machine consisting of a mixing-vessel, with the apparatus used in conjunction therewith.

Figure 1 is an end view; Fig. 2, a front view, partly in section; Fig. 3, a front view with the mixing-vessel removed, and Fig. 4 is a plan of the machine.

The framing of the machine consists of the two side frames, $a a$, connected together by a transverse frame, a^x , of corresponding depth.

On the side frames, $a a$, are erected the standards $a^3 a^3$, which support the hopper to contain the flour to be mixed. The upper part, b , of the hopper is of wood, while the lower part, b' , is a trough of cast-iron, with a longitudinal slit or opening along the bottom. There is, however, a low partition in the center of the hopper, which divides the slit into two parts or lengths, each of which is fitted with a slide, c , by which the slit may be closed. The slide is supported by guide-bars, screwed to the under side of the trough b' , and is provided with handles c' . The hopper is closed at the

top by a lid, b^2 , hinged to it, as is shown, and in the lid is an opening of sufficient size to admit of sacks of flour being emptied into the hopper. This opening is fitted with a cover, b^3 . Within the hopper are arranged agitators $d d$, which are employed to keep the flour in motion, so that it may run with regularity through the slits at the bottom when these are open. These agitators are blades fixed on the axis d' , which is kept in rotation when required by having a spur-wheel, e , upon it, which gears with another spur-wheel, f , and this latter is driven in a manner hereinafter described. The spur-wheel e is capable of sliding on the axis d' , so that it can be drawn out of gear when desired, and with this view the wheel is fitted with a handle, e' . The axis d' has a feather upon it to prevent the wheel e rotating independently of its axis. The flour, on descending from the hopper, falls into the mixing-vessel, and to distribute it evenly over the bottom thereof or over the dough therein the dusting-board g is used. This is mounted on the axis g' .

g^2 is an arm on the axis g' . It is connected by a rod, h , with the eccentric i^2 , fixed on the pinion i' , which gears with a spur wheel, j , on the axis d' of the agitators. The dusting-board g thus has an oscillating motion given to it, and the flour as it falls, coming against this board, is thrown by it first to one side and then to the other of the mixing-vessel.

The mixing-vessel k is made by preference of galvanized sheet-iron riveted together. It is mounted on three wheels. The stud-axes of the two hinder wheels, $k' k'$, are fixed to the bottom of the vessel, and the axis of the third or front wheel, k^2 , is carried by a fork at the lower end of a vertical spindle, k^3 , which is capable of turning in a bracket-piece riveted to the mixing-vessel, as is shown. The upper end of the spindle k^3 is squared to receive a handle, by means of which the mixing-vessel can be drawn from place to place, and by directing the handle to one or other side a corresponding direction will be given to the leading-wheel, and the vessel will thus be steered or guided. The bottom of the mixing-vessel k is made double, and the space inclosed is employed to contain warm water to keep the dough at the proper temperature for fermentation when the mixing is complete. The water is poured in at the opening k^5 and

run off when done with by the cock k^6 , or steam may be employed to warm the mixing-vessel, or gas may be laid on under it. In very hot climates it is necessary to cool in place of to heat the mixing-vessel k .

l is a portion of the front of the mixing-vessel which is removable to facilitate the taking the dough or paste out of the vessel. At other times it is held in its place by the catches k^3 .

The mixing-vessel is kept in its place in the machine during the mixing process by a bar, l , which bears on the front of the vessel. The bar has eyes at its ends, which pass over screws projecting from the side frames a , and it is secured by the hand nuts e' . Within the mixing-vessel are the mixers m . They are teeth made of wrought-iron and set in inclined positions on the cranked axis or bar m' . It has sockets formed at its ends, which are made square interiorly.

The way in which the mixer is carried and is actuated as shown in these drawings, and as is suitable for machines of very large size, is as follows:

n are standards which carry in suitable bearings tubular axes o . Through each of these axes a bar, p , passes. It is also further supported by a bearing, p' , and is squared at the end. These bars p are capable of sliding within the tubular axes, but are made to turn with them by means of feathers or otherwise. The squared ends of the bars p fit into the sockets at the ends of the mixer, so that when the two tubular axes o are driven they carry the mixer with them. Simultaneous motion is given to these two axes by the two large spur-wheels $f f$, mounted upon them.

r is a horizontal axis at the back of the machine. It is carried in bearings on the frames a , and is driven either by power or by a crank-handle applied at its end and actuated by manual labor. With this machine, however, power is more commonly employed. The axis r has at each end a pinion, r' , which gears with one of the spur-wheels f , and from them the mixer receives motion. The pinions r' are not fixed on their axis, but are capable of sliding on a feather. This arrangement is made in order that the speed of the driving may be varied, to effect which there are also other larger pinions, $r^2 r^2$, similarly mounted on the axis r , and these, when the pinions r' are out of gear, can be made to gear with the spur-wheels $s s$, of which there are two, one at each end of the machine. They are mounted on the tubular axes o . The axis r has also a fly-wheel, r^3 , upon it to keep the speed of rotation as nearly uniform as may be.

When the machine is desired to run fast—that is to say, when only a part of the flour has been let down and mixed with the water and before the dough is stiff—the larger pinions r^2 are made to gear, but as soon as the dough stiffens these are thrown out and the smaller pinions r' thrown into gear, so that the machine may be driven at a slower speed. In order to throw these pinions in and out of

gear, there is a collar on each pair of pinions $r' r^2$, which is embraced by a fork, t , capable of sliding to and fro in guides in the frame. These forks are each attached to connecting-rods $u u$, and these are pin-jointed to a lever, v , mounted on a fixed center, v' . This arrangement causes the pinions at the opposite ends of the machine to move in unison.

w is the handle, by which the pinions are thrown in and out of gear. It is mounted on the fixed center w' , and at its inner end is pin-jointed to one of the forks t , as is shown. This lever can be locked to the frame by a pin, w^2 , either in position to retain in gear the pinions $r' r^2$ or the pinions $r^2 r^2$, as may be required. One of the bearings of the axis r is carried by a bracket, a^4 , from one of the side frames. When the dough or paste is completely mixed, it becomes necessary to remove the mixer from the mixing-vessel, and for this purpose the bars or axes p have to be drawn back. To effect this each of the axes p has a collar on it at p^2 , which is embraced by a fork on one of the levers x . These levers are mounted on fixed centers at x' , and each of them at its inner end is pin-jointed to one of the connecting-rods y . These rods are connected to the lever z . A is the handle by which this gear is worked. It is fixed on the horizontal axis A' , and at its inner end it has an arm, A^2 , projecting downward and entering a slot in one of the rods y . Thus it will be seen that by turning the handle A the axes $p p$ of the mixing-vessel can be withdrawn or protruded out, as may be required. There are holes in the side of the mixing-vessel, through which the axes $p p$ can pass freely.

Another method of carrying and actuating the cranked-mixer axes m' , and which is preferable, except where the machines are of very large size, is hereinafter described.

Connected with the frame of the machine are arms a^5 , tied together by a bar, a^6 , and having friction-wheels $a^7 a^7$ mounted upon them. These arms are to support a lid, with which the mixing-vessel is fitted, when the lid is out of use, and the friction-wheels are to enable the workman without difficulty to run the lid onto or off from the mixing-vessel.

I would remark that it is only in machines of very large size that it is desirable to drive the mixer-axis m' from both ends. In machines of ordinary size it is only necessary to drive it from one end, and this greatly simplifies the arrangement of the gearing. A plan of a machine thus arranged is shown at Fig. 5 of the drawings B. In this machine, also, but one axis, p , is employed, the mixer-bar at the other end being supported simply in a socket formed in the end of the mixing-vessel. The axis p employed is not made to slide, and the method of holding and driving the mixer-bar m' is modified to admit of this in a manner hereinafter described. This is a change also which greatly simplifies the arrangement of the machine, and it forms an important part of my invention.

The machine has a movable mixing-vessel, k , which is received between the two standards a of the frame, and is held in its place by hooks or catches l^x at the back, in place of by the bar l , as before. The standards x are connected together by a bed-plate, as is shown. The axis p is made in two parts, the bearings of one part being carried by the standard and that of the other by the end of the mixing-vessel. If the machine, however, were made with a fixed mixing-vessel it would not be necessary to make the axis in separate parts. It is required when a movable mixing-vessel is employed to allow the vessel to be run in and out, but when the vessel is in its place the axis works as if it were in one piece, there being a fork formed in one part of the axis which then embraces a cross-head on the other part of the axis. The standards a also carry the axis r . This axis, however, has pinions r' and r^2 at one end of it only, and similarly there is but one wheel, f , and one wheel s . The pinions r' and r^2 have a handle attached to them, by which they are moved in and out of gear. In this machine, also, the fly-wheel r^3 is not mounted on the axis r , but this axis is carried by a separate standard and has fixed on it a spur-wheel, r^4 , which gears with another larger spur-wheel, r^5 , on the axis r . This arrangement, as it causes the fly-wheel to revolve more rapidly than the axis r , allows of a lighter wheel being used without any loss of efficiency.

In order to give sufficient strength to the mixer-bar to allow of its being driven from one end only, I strengthen it in the angle by means of a diagonal tie.

Fig. 6 is a side view of a mixer-bar, m' . Thus strengthened, m^x is the diagonal tie. It extends, as the drawings show, from the square driving-socket of the mixer-bar to the horizontal portion thereof.

Figs. 7 and 8 are end views of the mixer-bar, (shown at Fig. 6,) and Fig. 9 is a transverse section of the same. It will be seen that the form of the mixer m is somewhat varied. That indicated in these figures is very effective. In this case, in order that the mixer-bar m' may be movable, as is required, the driving-socket of the bar is notched on one side, as is shown by the end view. This allows it readily to be put in or removed from the axis p , and to prevent it falling off this axis when in the course of each rotation the notch is uppermost. A semicircular lip is formed in the mixing-vessel immediately under the axis, and this receives and supports the boss or exterior of the driving-socket of the mixer-bar. The end of the driving-axis p I do not in this case make square in section, but I make it to correspond in form with the notch in the mixer-bar, into which it is to fit. The mixer-bar may also be prevented falling off the axis p by means of a ring made to slide over the point of junction.

If desired, the mixing-vessel may be divided into two compartments by a central partition,

and then two mixer-bars are used, one in each compartment. In the partition there is a bearing carrying a short axis, which receives at each end the end of one of the mixer-bars, which it retains, as already described, either by means of a lip or by means of a sliding ring. When the axis p is turned, both mixer-bars will be driven, and they are arranged so that when the mixers m of one bar are in the dough those of the other are up out of it, consequently the power required to drive two mixer-bars so arranged will be more uniform than when one bar only is used.

In some cases, when employing a flour-hopper above the mixing-trough, I dispense with the vibrating dusting-board g , and in place thereof I make a portion of the slide c of perforated metal or gauze. The motion of the stirrers within the hopper will insure the passage of a continuous shower of flour through the perforated portion of the slide.

Fig. 10 is a front view, and Fig. 11 a vertical section, of a portion of a flour-hopper thus constructed.

In making the best bread it is customary always to sift the flour. When this is desired, I mount a rotary sieve in the hopper over the mixing-vessel, and in place of putting the flour direct into the hopper, I put it into a chute at the side, from whence it passes through the sieve and into the hopper.

Fig. 12 is a vertical section of the upper part of a hopper with a rotary screen combined with it.

D is the chute into which the flour is placed.

E is the axis on which the rotary screen F is fixed. This screen is conveniently made of perforated metal or wire-gauze, or it may be made of woven fabric.

The axis E is caused to rotate by means of a pinion, G ; at its end, which gears with another pinion, H , which is either turned by means of a crank-handle or it may be thrown into gear with the wheel e , if sifting and mixing be required to go on simultaneously.

I is an inclined propeller, mounted on the axis E within the chute D , to draw the flour forward into the screen.

The apparatus which I employ to raise the dough or paste in the mixing-vessel, in order that it may be removed therefrom, is shown at Figs. 13 and 14. (See Drawing C.) This scoop is fixed on the mixer-bar when it is required to discharge the dough.

Fig. 13 is a side view, and Fig. 14 is a plan, of the scoop.

a are two side plates; b , a bottom plate, and c a central partition. These parts form a double scoop, and it is of such a size as just to fit in between two of the mixers in the mixer-bar, entering into the notches $c' c'$ of the scoop. The scoop is secured by a bolt passing through it and through the ends of two of the mixers m . The double scoop raises two pieces of dough at each rotation--one on the plate b , and the other on the plate C .

The drawings D show a machine of small size and simple in its construction. It is such a machine as is adapted for use in small households. It is made with the axis p fixed as described in respect to Fig. 5.

Fig. 15 is a vertical section, Fig. 16 an end view, and Fig. 17 a portion of a plan, of the machine. The mixing-vessel is arranged as in the machine last described, but is smaller and not provided with feet, as this machine is intended to stand on a table.

The casting a^8 , which is bolted onto one end of the machine, is so made as to case in the wheels f and r' . The wheel f is fixed directly on the axis p , one bearing of which is carried by the bracket a^8 and the other by the side of the mixing-vessel. A front view of the bearing within the mixing-vessel is shown separately at Fig. 18, and a plan of the same at Fig. 19. (See Drawing C.) In the same figures a portion of the axis p and also of the mixer-bar m' is shown, as will be seen. The bearing has a semicircular lip, k , upon it. This, as already mentioned, is to prevent the mixer-bar m' falling off the axis p when the notch in the boss of the mixer-bar is uppermost.

By making the axis p stationary—that is to say, so that it cannot slide endewise—I am enabled, as the drawings show, to bring the spur-wheels close up to the side of the mixing-vessel, and this is the case, whatever be the size of the machine, where a fixed mixing-vessel is employed. The axis r is carried in bearings, one of which is in the casting a^8 and the other in a bracket fixed to the back of the mixing-vessel.

No fly-wheel is employed in machines of the small size shown in these drawings, and for the sake of simplicity of construction the pinion r' is not made to slide in and out of gear.

What I claim as my invention, and desire to secure by Letters Patent, is—

1. The dough-mixer hereinbefore described, composed substantially of prongs secured to a cranked axis or bar, so that it may be readily withdrawn from the dough when the axis is uppermost.

2. The combination of a stationary frame to support the gearing, by which the dough-mixer is worked with a removable mixing-vessel, in such manner that the connection of the gearing with the dough-mixer in the mixing-vessel may be disconnected to permit the

dough to be conveyed in the mixing-vessel to any part of the bakery, substantially as herein set forth.

3. The combination of the dough-mixer with a flour-hopper and flour-agitators, or their equivalent, whereby the flour thrown in mass into the flour-hopper is delivered gradually to the mixing-vessel during the mixing of the dough, substantially as herein set forth.

4. The combination of the flour-hopper and its agitators, with variable slides to regulate the discharge of flour to the mixing-vessel beneath, substantially as herein set forth.

5. The combination of the flour-hopper and the mixing-vessel, with a dusting-board between the two to distribute the flour into the mixing-vessel, substantially as herein set forth.

6. The combination of the flour-agitators or other moving appurtenances of the flour-hopper with the dough-mixer by a removable connection, so that the former may be thrown out of gear when the flour is exhausted, substantially as herein set forth.

7. The combination of the dough-mixer with change gearing, so that it may be moved rapidly when the dough is thin and more slowly when the dough becomes tough, substantially as herein set forth.

8. The combination of the dough-mixer with duplex gear, (at the two ends of the machine,) so that an equal motion is communicated to both ends of the dough-mixer simultaneously, substantially as herein set forth.

9. The combination of the driving-spindles of the dough-mixer at the two ends of the machine with one shifting-lever, so that both driving-spindles can be simultaneously withdrawn from the dough-mixer, substantially as herein set forth.

10. The combination of a mixing-vessel fitted with a mixer with a jacket, forming a double bottom to permit the temperature of the mixing-vessel to be varied by the application of water or steam, substantially as herein set forth.

E. STEVENS.
